poration of Delaware

Application May 12, 1942, Serial No. 442,638

10 Claims. (Cl. 210—7)

The invention hereof primarily relates to and revolves about a novel form of clarification or thickening apparatus embodying a single tank structure having a liquid-holding section that is divided by a partition or partitioning means into functionally separated primary and secondary compartments that are in constant hydraulic communication through a passage area left because of the partition being only a partial one and certain other parts or features arranged in novel functioning relationship with respect thereto.

The tank structure or tank has a bottom, preferably with a depressed portion providing a sump, and a marginal wall rising from the bottom whereby a liquid-holding section is provided within the tank. In the form of construction illustrated this sump is located at the bottom of the primary compartment. This is the preferred location for the sump. However, according to certain broad aspects of the invention the sump, if provided, is not necessarily located immediately below the primary compartment. The tank is preferably equipped with suitable sediment-collecting and transferring mechanism that includes sediment-engaging and impelling elements which are operable over the floor or bottom of the tank and functionable to transfer sedimented material engaged thereby towards and into the sump. The sump has sediment-withdrawal means for from time to time passing sedimented material therefrom to the exterior of the tank.

In the form of construction shown the tank is rectangular in plan and is equipped with a sediment-transfer mechanism embodying a conveyor of the endless type with a lowermost section or lowly positioned conveying element that is movable longitudinally and along the floor or bottom of the secondary compartment through the passage area below or provided by the partitioning means and continues along the floor or bottom of the primary compartment until it has delivered the sludge transferred thereby into said sump. The tank—preferably the primary compartment thereof—may be provided with a scum-receiving trough and the conveying means referred to may also include a scum-transferring element disposed for operative association with the scum trough whereby the scum-transferring element can convey or push floating scum engaged thereby towards and into said trough.

According to the invention a feed-receiving and distributing means is provided for the primary compartment, and a collecting launder or other suitable collecting means is provided for

receiving supernatant liquid passing therewith from the upper interior portion of the primary compartment.

In the rectangular form of tank illustrated it is divided by a vertically and transversely-extending partition terminating a distance above the bottom of the tank so that the primary and secondary compartments have horizontal disposition and are in constant hydraulic communication whereby there is a common level for the liquid in both compartments. This collecting launder or means is forwardly spaced a substantial horizontal distance from the feed-receiving and distributing means and where a scum trough is employed the collecting launder is preferably disposed between the partition and the scum trough. In other words, the horizontal spacing or arrangement just referred to calls for the feed-receiving and distributing means being located at the rear or receiving end of the tank, the collecting launder or collecting means proximate or in rear of the partition and the scum trough between the two preferably close to but somewhat in the rear of the collecting launder.

As to the secondary compartment, this has a liquid feed-distributing means preferably close to or immediately ahead of the partition and an effluent launder horizontally spaced from the liquid feed and distributing means, preferably at the front or effluent discharge end of the tank. This effluent launder, or liquid overflow means as it may be sometimes referred to, has an overflow edge or section at sufficient height or elevation to determine the normal surface level of the liquid within the tank.

The clarification tank or thickening apparatus which has just been referred to has been designed primarily for use in sewage disposal systems wherein there is employed in cyclic arrangement with the tank or thickening apparatus a biologic treating means essentially embodying a bed or beds of discrete material having biologically active organisms therein or, as otherwise expressed, having biologically active organisms upon the surface of the discrete material constituting the bed or beds. This novel form of tank is arranged and employed in a novel manner in association with such biologic treating means as will hereafter more fully appear. The clarification tank or thickening unit comprising the tank has use, however, in other fields and the tank and the parts associated therewith can be brought into novel operative relationship in diverse ways as will be manifest from that which follows:

In each form illustrated some of the liquid collected from the primary compartment by the collecting launder or means referred to is ultimately passed by suitable means that include piping, pumping means, and some form of biologic treating means into the feed-distributing means for the subsequent compartment. In other words, means is provided whereby some of the liquid from the collecting launder of the primary compartment is pumped and delivered into the feed-distributing means of the secondary compartment. According to certain of the arrangement illustrated some of the liquid from the primary collecting launder or means may be passed for a biologic treatment through only one bed of discrete material, while according to other arrangements it may be subjected to treatment in a plurality of beds before ultimate delivery into the feed-distributing means for the secondary compartment. Such bed provides biologically active organisms that decrease the biologic oxygen demand of polluted liquid passing therethrough. From that which will follow one will see that various modes of flow and distribution is obtained or realized by the piping arrangement or systems shown, each and all of which will be more clearly brought out in conjunction with the specific description relating to the systems or flow-sheets hereinafter referred to.

Other features of construction and further objects and functional aspects of the invention will be manifest and brought out by the detailed description that follows and are particularly pointed out in and by the appending claims.

In the following description and in the claims parts will be identified by specific names for convenience but they are intended to be as generic in their application of similar parts as the art will permit.

In the accompanying drawings which constitute a part of this specification, there have been illustrated the best and most characteristic embodiments of the invention known to the undersigned, but such embodiments are to be regarded as typical only of many possible embodiments and the invention is not to be limited thereto.

In said drawings:

Fig. 1 is a plan view—partially in horizontal section—of a sewage treating system wherein the plural-compartment rectangular tank is operatively connected in association with a laterally disposed biologic treating means having a single bed of discrete material, to wit, a biologic treating bed which is in the form of a trickling filter.

Fig. 2 is a view showing the tank in vertical longitudinal section, to wit, primarily as a view taken on the vertical plane indicated by the broken line 2—2 of Fig. 1, looking in the direction of the arrows. In this figure, however, a portion of the tank structure has been broken away so as to show the relative vertical elevation of the trickling filter which is laterally disposed with respect to the tank structure. In this connection it will be noted the trickling filter is at elevation substantially lower than that of the normal surface level of the liquid within the tank and that the trickling filter is shown in vertical section.

Fig. 3 is a detailed vertical sectional view illustrating more clearly the central portion of the tank in the region of the vertically and transversely extending partial partition of the tank.

Fig. 4 is a plan view of the same type of plural-compartment tank connected in operative asso-

ciation with a laterally disposed biologic treating means provided by a single trickling filter.

Fig. 5 is a vertical sectional view of the tank taken as on the vertical plane indicated by the broken line 5—5 of Fig. 4 looking in the direction of the arrows. In Fig. 5 a certain portion of the side wall of the tank has been broken away to show a basin or well providing a liquid commingling member. In the case of Figs. 4 and 5 the trickling filter is at elevation substantially above that of the normal surface level of the liquid within the tank. The trickling filter in this instance is also shown in vertical section.

Fig. 6 is a plan view showing the plural compartment tank connected in operative arrangement with laterally disposed biologic treating means provided by two spacedly positioned trickling filters.

Fig. 7 is a vertical sectional view of the tank taken as on the vertical plane indicated by the broken line 7—7 of Fig. 6 looking in the direction of the arrows. In this view the laterally disposed trickling filters are at elevation higher than that of the tank and are shown in vertical section.

Reference will now be made to the drawings in detail:

Like reference characters indicate parts functioning the same or substantially alike wherever they appear.

The plural compartment tanks

The tanks employed in each of the sewage treating systems illustrated are substantially the same except that no scum weir is shown in the form illustrated in Figs. 4 and 5. It is shown, however, in the other figures.

The tank or tank structure generally designated by 10 has a bottom section or floor providing member 11 having a depressed portion 12 providing a sediment-receiving section or sump 13. The tank also has a marginal wall 14 rising from the bottom 11. This marginal wall includes a vertically and transversely extending rear end wall 15 at the feed receiving end of the tank, a front end wall 16 at the effluent discharge end of the tank, and vertically and longitudinally extending side walls 17 and 18. The tank is also provided with a vertically and transversely extending intermediate member in the form of a partial partition 19 extending downwardly within the liquid-holding portion of the tank but terminating at 20 a distance above the bottom floor of the tank whereby it, with the spaced side walls 17 and 18, defines a flow passage area 21 leading rearwardly from the liquid-holding section or compartment 23 which is functionally ahead of the partition 19 and into the liquid-holding section or compartment 22 which is at the rear of the partition. In other words, this partial partition divides the tank into functionally separated primary and secondary quiescent liquid-clarifying zones or compartments heretofore respectively designated as 22 and 23. These compartments are in constant hydraulic communication with each other through the passage area 21 referred to. The primary compartment 22 is at the feed-receiving end of the tank and the secondary compartment is at the front or effluent discharge end of the tank.

The primary compartment has a feed-receiving and distributing means collectively designated as 24, and which is provided by a feed-

receiving and distributing launder 25 and a baffle member 26. This baffle member 26 extends downwardly from the top portion of the tank a substantial distance within the liquid-holding section of the tank and it is forwardly spaced with respect to the rear end or wall 15 of the tank to provide a downwardly directed flow-path 27 whereby the incoming liquid is localized within the rear or receiving end of the tank until it is distributed into and across the lower rear end portion of the primary compartment 22. This flow-path 27 immediately overlies the sump 13 whereby any quickly settleable solids can drop immediately into the sump. A sediment-discharge conduit 28, controlled as by a stop valve or gate 29, leads from the sump 13, or as otherwise expressed, from the lower interior compartment 22. This valve-controlled conduit 28 is relied upon for passing, according to operative requirements, sedimented material received within the sump 13.

The primary compartment 22 is also provided with a collecting launder 30 that is preferably disposed immediately behind the partial partition 19 and which is at elevation for receiving the partially-treated supernatant liquid flowing thereinto from the compartment 22. This collecting launder 30 serves as a liquid-collecting means for the primary compartment and could readily be provided by a slotted or apertured pipe since it is primarily relied upon as a normally submerged collecting means and is not relied upon for establishing or determining the normal surface level of the liquid within the tank. Because of the submerged position for the collecting launder 30 it is sometimes referred to as a submerged collecting means or member for the primary compartment 22. The liquid collected thereby may be supernatant liquid or liquid material taken from any elevation in the tank and may even contain a considerable portion of solid material such as is delivered from the secondary compartment by the sludge-collecting means.

As to the secondary compartment this has a liquid-receiving and distributing means collectively designated as 31. This distributing means embodies a receiving launder 32 and is preferably provided with a baffle 33 that is spaced a short distance ahead of the launder 32 whereby a downwardly directed flowpath 34 is provided from which downflowing liquid is distributed within and across the lower rear end portion of the secondary compartment 23. At the forward or discharge end of the tank there is provided an effluent launder 35 for receiving supernatant liquid of the secondary compartment. This launder 35 has an overflow weir or edge 36 that determines the normal surface level of the liquid within the tank. Means in the form of a pipe or outflow conduit is provided at 37 by which liquid overflowing into the launder 35 may be passed therefrom and it is from this tube or conduit that liquid is released from the system in quantity corresponding to the quantity of feed supplied for treatment.

The compartments 22 and 23 provide horizontally disposed quiescent sedimentation zones and it will be clear that settleable material can gravitate from the liquid therein and deposit as sediment or sludge on the underlying floor portion or bottom of the tank. In order to effect a progressive transfer of this sedimented material from diverse sections of the tank bottom to and into said sump there has been provided an end-

less type of conveyor collectively referred to as 40. This conveyor embodies transversely spaced endless members as endless chains 41 and supporting sprockets or guiding wheels therefor as 42, 43, 44, 45 and 46. These endless chains 41 have connected thereto transversely extending sediment-impelling elements in the form of scrapers or raking blades 47. These scraping elements extend across or transversely of the tank over the floor or bottom thereof and are longitudinally spaced with respect to each other and are carried by the endless members 41. Each endless chain 41 comprises a forwardly movable upper section or strand 50, a descending vertical section 51, a forwardly movable longitudinal section 52 disposed at elevation for passing below the lower edge of the partition 19 without interference therewith, a lowermost section 53 movable rearwardly along and immediately over the bottom 11 of the tank and a rising vertical section 54 reaching to the upper section 50. A transversely extending vertical baffle 48 is disposed between the descending section 51 and the overflow edge 49 of the collecting launder 30. In a tank structure where a scum launder as 57 is employed this baffle is located between the scum launder 57 and the edge 49 of the collecting launder 30.

In the forms shown in Figs. 1 to 3 and in the forms shown in Figs. 6 and 7, there is indicated the scum trough 57 referred to. In the form shown the scum trough embodies a cylindrical member 58 slotted at the top to provide a receiving opening for the scum passed thereto. This cylindrical member is mounted in seats 59 and has a handle 60 whereby the position of the slotted portion 55 of the trough 57 relative to the general level in the tank can be adjusted. Scum is passed from this scum trough or collector 57 through a tube or conduit 61 that extends from the inside of the tank through the side wall to the exterior of the tank. It will also be noted that the scraping members or flights 47 of the uppermost strand or section 50 of the endless conveyor move forwardly—in the direction of the arrow proximate that section—and function to impel or push scum longitudinally along the primary section of the tank into the trough 57.

The system of Figures 1 to 3

In this system the biologic treating means is in the form of a trickling filter having a bed of discrete material 70 within a containing structure 71 having a collecting section 72 for receiving filter effluent. As this trickling filter bed is at elevation substantially lower than that of the general level of the liquid in the tank, liquid can flow by gravity from the collecting launder 30 through pipe or conduit 73, and from the effluent launder 35 through the pipe or conduit 75, and from the pipes 73 and 75, which may be viewed as branches, to a lateral main pipe 77 and upflow pipe 78 thence into a rotary distributor 79 by which any liquid flowing thereinto is relatively uniformly distributed over the trickling filter bed. The pipe 73 is provided with a positionable control valve 74 and the pipe 75 is provided with a positionable control valve 76. The valve-controlled pipe 73, pipe sections 77 and 78, and rotary distributor head 79 may be viewed as a means for selectively transferring and distributing a quantity of liquid from the primary collecting launder 30 to the bed of the trickling filter or biologic treating means 70. The valve-con-

System of Figures 4 and 5

trolled pipe 75, pipe sections 77 and 78 and the rotary distributing head 79 may be viewed as means for selectively passing effluent from the secondary effluent launder 35 to the bed of the trickling filter or biologic treating means. From the sump or receiving section 72, of the filter casting 71, effluent from the filter bed is passed along the pipe or section conduit 80 from which it is conveyed by pump 81 into the pipe section 82 and valve-controlled branches 83 and 84 selectively and respectively into the feed pipe 6 and thusly into the feed-receiving and distributing means 24 for the primary compartment and into the liquid-distributing means 31 of the secondary compartment. The pipe section 80, pump 81, pipe section 82 and the valve-controlled pipe section 83 constitute means for selectively passing and delivering filter effluent into the feed-receiving and distributing means for the primary compartment. Likewise, the pipe section 80, the pump 81, the pipe section 82 and the valve-controlled section 84 constitute means for selectively passing and delivering filter effluent into the liquid-receiving and distributing means for the secondary compartment.

From that which has preceded, it will be manifest that partially treated supernatant liquid from the primary collecting launder 30 and clarified supernatant liquid from the secondary effluent launder 35 is caused to mingle and be passed in selected quantities to the bed of the biologic treating means and that the biologically-treated effluent from this bed can be selectively passed some to the rear end of the primary compartment and some into the rear end section of the secondary compartment and that the liquid in each compartment is held in condition favorable to the sedimentation of settleable solids therein.

It will also be noted that if and when desired a sufficiently large quantity of liquid can be passed as from the collecting launder 30, or from the collecting launder 30 and the effluent launder 35, whereby a relatively large quantity can be delivered into the secondary distributing means 31, to wit, in quantity greater than the amount passing into the effluent launder 35 whereby there will be a resulting back flow of liquid from the secondary compartment to the primary compartment, all of this taking place even though there is a release from the effluent launder of a quantity of liquid corresponding to the quantity of liquid supplied for treatment.

The valve-controlled pipe line 73, the pipe sections 77 and 78, the liquid-distributing head 79, the filter sump 72, the conduit 80, the pump 81, the pipe section 82, and the valve-controlled pipe section 84 may be viewed as collectively constituting means embodying a pump for passing at will any desired quantity of liquid from the primary collecting launder 30 into the secondary liquid-distributing means 31 whereby any control condition of back-flow from the secondary compartment through the passageway 21 into the primary compartment can be attained. This back-flow tends to discourage and in fact can be relied upon to prevent the passage of liquid material from the primary compartment into the secondary compartment, a thing which would ordinarily take place if such excess quantity of liquid received in the secondary compartment over that released from the secondary compartment were not deliberately planned and attained.

In this system the biologic treating means is in the form of a trickling filter having a bed of discrete material 70 within a containing structure 71 having a collecting section 72 for receiving filter effluent trickling thereinto. This trickling filter is at elevation substantially higher than that of the general level of the liquid within the tank. The elevation of the trickling filter is sufficiently high whereby the filter bed effluent can flow by gravity from the receiving and collecting section 72 through a valve-controlled pipe 90 into the launder 32 of the liquid-receiving and distributing means 31 for the secondary compartment. This elevated position of the trickling filter therefore necessitates the employment of means essentially comprising a pump for passing any liquid from the multi-compartment tank upwardly to and upon the trickling filter bed.

According to the arrangement of this system supernatant liquid from the primary compartment is received in the primary collecting launder 30 and is passed from this launder through pipe or conduit sections 91 and 92 into a basin or well 93. Supernatant liquid from the secondary compartment overflows into the effluent launder 35 and a quantity of the overflowed liquid passes from the tank through the outflow pipe 37. The quantity of liquid thus released from the system through the outflow pipe 37 corresponds to the quantity of incoming feed that is supplied to the tank by the influent pipe 6 and the feed-distributing means 24. A quantity of the overflowed liquid received in the effluent launder 35 is passed by the pipe or conduit sections 94 and 92 into the well 93. In this connection it will be noted that the well receives a quantity of partially treated supernatant liquid of the primary compartment that is passed thereto from the collecting launder 30 and a quantity of the relatively clarified supernatant liquid of the secondary compartment that overflows into the effluent launder 35 and of which some is passed to this well. The liquids received in this well are either commingled therein or effectively mixed before delivery to and distribution over the bed of the trickling filter and for this reason the basin 93 is sometimes referred to herein as a commingling well. The liquid is continuously passed from this well 93 by a conveying and distributing means comprising pipe or conduit section 95, pump 96, pipe or conduit section 97, and a rotary distributor head 98 by which the thus pumped liquid is relatively uniformly distributed over the top of the trickling filter bed, or as otherwise expressed, upon the top of the bed of discrete material of the biologic treating means.

The tank of this system and the mode of operation of the parts associated therewith will be manifest from that which has preceded. It will be pointed out, however, that according to a preferred mode of operation there is a passing of liquid into the commingling well in quantities sufficient for a passing of the commingled liquid to the trickling filter bed and for a like passing of the trickling filter bed effluent into the liquid feed and distributing means 31 for the secondary compartment 23 in quantities greater than that of the supernatant liquid passing from said secondary compartment into the effluent launder 35 with the result that there is a certain quantity of back-flow liquid continuously passing from the secondary compartment 23 through the passage 75 area 21 into the primary compartment 22. This

back-flow of liquid functions in cooperation with the sediment-transferring mechanism 40 to facilitate the transfer of sedimented material from the secondary compartment towards the primary compartment. The back-flow also resists or avoids any tendency for a counter or forward passage of sedimented material from the primary compartment 22 into the secondary compartment 23.

System of Figures 6 and 7

In the system illustrated by these figures the tank embodies the features of construction shown in connection with the system shown in Figs. 1 to 3 inclusive. The primary difference between the system of Figs. 6 and 7 and the systems of the other figures revolves about the employment of a biologic treating means having a plurality of beds of discrete material with biologic organisms on the material constituting the bed. In other words, the biologic treating means of this system comprehends that which may be viewed as a primary trickling filter and as a secondary filter. The primary trickling filter is shown connected principally in association with the primary compartment of the tank whereby there is a repetitive cycling of the liquid undergoing treatment in the primary compartment and in the primary filter. The secondary trickling filter bed is connected in association with the secondary compartment in a manner whereby the liquid of the secondary compartment is cyclically treated by repetitive passage as between it and the secondary trickling filter. It will be noted, however, that an interconnection is provided whereby some of the effluent of the primary trickling filter is passed into a receiving well or basin that receives some of the supernatant liquid from the secondary compartment whereby that well functions as a commingling well receiving a quantity of liquid from the primary section of the system and a quantity of liquid from the secondary section of the system.

In the arrangement shown by these figures, the trickling filter beds are at elevation substantially higher than that of the normal surface level of the liquid within the tank whereby filter effluent can gravitate and be selectively distributed for passage back into certain compartments of the tank or into a receiving well or basin disposed in associated relationship to the tank and from which it is pumped.

As to the primary section of the system, this embodies a primary trickling filter 100 that includes a bed of discrete material 70, and a casing structure 71 therefor having a filter effluent collecting section 72 from which the filter effluent flows by gravity through a pipe or conduit section 101 and a valve-controlled branch 102 to and into the feed pipe or conduit 6, thence into the primary feed distributing means 24.

Another valve-controlled branch 103 leads from the pipe section 101 to a pipe section 104 that delivers into a commingling well or basin 105. Supernatant liquid from the primary compartment passes into the collecting launder 30 and flows downwardly therefrom through the pipe or conduit section 106 into a well 107 provided for receiving partially treated liquid from the primary compartment. The partially treated liquid is passed from this well 107 to and distributively delivered upon the bed 70 of the primary trickling filter through the medium of pipe or conduit section 108, the pump 109, pipe or conduit section 110 and the rotary distributor head 98.

As to the secondary section of this system it includes the secondary trickling filter 120 and the secondary compartment of the tank. This trickling filter has the bed of discrete material 70 the casing 71 and filter effluent is passed from the collecting section 72 thereof by the pipe or conduit section 121 into the secondary liquid-receiving and distributing means 31, more particularly into the liquid-receiving launder 32 thereof.

- 10   Supernatant liquid from the secondary compartment 23 overflows the edge 36 into the effluent launder 35 from which a quantity thereof is released through the outflow pipe 37 and passes from the system or treating unit, while a quantity thereof is passed through a valve-controlled pipe 112 and the pipe section 104 into the commingling well 105 previously referred to. The liquid within the commingling well, namely, some of the liquid which is passed thereto from the effluent side of the primary biologic treating means and some of the liquid received thereto from the effluent launder 35 is passed as commingled liquid from the well 105 and is distributively delivered to the top of the secondary trickling filter through the medium of the pipe or conduit section 122, the pump 123, the pipe or conduit section 124 and the rotary distributing head 98 by which it is distributed in a relatively uniform manner over and upon the top of the secondary trickling filter bed.

From that which has preceded it will be manifest how the different portions of the systems can be brought into operative arrangement, but here again attention is called to the fact that according to the desire of a particular operator, or according to the type of operation to be carried out in the system, one can effect a transfer of a quantity of liquid into and from the liquid-receiving and distributing means 31 for the secondary compartment 23 that is greater than that of the liquid which overflows from said compartment past the overflow weir or edge 36 into the secondary effluent launder 35 whereby there is realized a continual back-flow of liquid from the secondary compartment 23 into the primary compartment 22. This back-flow or passage of a substantial quantity of liquid from a secondary or subsequent treating compartment of a clarifying tank into a primary or preceding compartment of such tank and in the same direction as that in which sediment is passed from the secondary or subsequent compartment into the primary compartment or preceding compartment of such tank is believed to be new in apparatus or units of this general class and is indicative of a feature of construction which can be advantageously employed in multi-compartment tanks or clarifying units which may have embodiments or constructions quite different in appearance and arrangement from that shown in the horizontal tank arrangement described herein.

What is claimed is:

1. Apparatus for the continuous treatment of polluted liquids comprising a sedimentation tank; partial partitioning means dividing the tank into hydraulically communicating primary and secondary clarifying compartments; means for removing sediment from said compartments; means for feeding polluted liquid to be received by the primary compartment, means for releasing clarified purified effluent from the secondary compartment at a rate corresponding to the rate of feed to the primary compartment, aerobic biologic means for treating impure liquid for decreasing the biologic oxygen demand of the thus

treated liquid, means for transferring a quantity of clarified impure supernatant liquid from the primary compartment to said aerobic means, means for delivering a quantity of liquid discharged from said aerobic means to the secondary compartment, and pump means for passing liquid in transit from the primary compartment through the aerobic means to the secondary compartment at a rate greater than that at which clarified purified liquid is released from the secondary compartment sufficient so that contaminating migration is minimized of impure liquid from the primary compartment past the partition into the treated liquid in the secondary compartment.

2. Apparatus according to claim 1 with the addition of means for recycling liquid between the secondary compartment and the aerobic means.

3. Apparatus according to claim 1 wherein said sediment removing means comprise means for impelling sedimented material settling from the liquid of the secondary compartment into the lower portion of the primary compartment to be there joined with sediment settling from the liquid of the primary compartment, and means for removing such joined sediment from the primary compartment.

4. Apparatus for the clarification of polluted liquids comprising a rectangular tank having a bottom and walls adapted to hold a body of liquid being treated, a partition having a lower edge portion vertically spaced from the bottom of the tank and dividing the tank transversely and functionally into primary and secondary clarifying compartments but leaving hydraulic communication between them, a sediment sump associated with the primary compartment, means for impelling sediment from both said compartments that collects on the tank bottom whereby sediment from the secondary compartment is passed to the primary compartment and sediment from the primary compartment is passed to the sump, feed-receiving and distributing means for the primary compartment, liquid-receiving and distributing means for the secondary compartment, a collecting launder for receiving supernatant liquid from the primary compartment, an effluent launder for receiving supernatant liquid overflowing thereinto from the secondary compartment, means for withdrawing liquid from said collecting launder of the primary compartment for subjecting the withdrawn liquid to further treatment and for passing at least some of the further treated withdrawn liquid to the liquid-receiving and distributing means of the secondary compartment, and means for passing to discard effluent from the effluent launder of the secondary compartment.

5. Apparatus according to claim 4 in which there is means for passing some of the withdrawn further treated liquid to the feed-receiving and distributing means for the primary compartment, and in which there is means for controlling the amount of effluent passing from the effluent launder of the secondary compartment to proportion it relative to the further treated liquid fed to and distributed within said secondary compartment whereby there is maintained a hydraulic imbalance that effects a liquid flow from the secondary compartment to the primary compartment.

6. Apparatus for the purification of polluted liquids comprising a tank having a bottom and walls adapted to hold a body of liquid being treated, a partition dividing the tank func-

tionally into primary and secondary clarifying compartments, means providing a submerged flow passage area extending between a lower portion of the secondary clarifying compartment and the primary compartment whereby said compartments are in constant hydraulic communication, means for feeding each compartment separately, means for supplying liquid to be treated whereby it is ultimately delivered into the primary clarifying compartment through the feeding means therefor, a separate launder for receiving clarified effluent from each compartment, a sediment sump for and directly below only liquid within the primary compartment, means for passing sedimented material from said sump, a primary biologic trickling filter bed, means for passing effluent from the primary compartment to the bed and for returning filter-bed discharge as augmented feed to that compartment, a secondary biologic trickling filter bed, means for passing a quantity of effluent from the secondary compartment to the secondary filter-bed and for returning filter-bed discharge to that compartment, means for passing a quantity of effluent from the secondary compartment to discard, and combined means for impelling sediment from both the secondary and primary compartments to said sump while avoiding sliding passage of sediment from the primary to the secondary compartment.

7. In operative combination a liquid-holding tank of the class described having a bottom, a marginal wall rising therefrom, partitioning means functionally dividing the liquid-holding region of the tank into primary and secondary compartments in constant hydraulic communication through the passage area hereafter referred to, and means providing passage area leading from the lower portion of the secondary compartment toward the primary compartment; feed-receiving and distributing means for said primary compartment; supernatant liquid-collecting means disposed at the upper portion of said primary compartment; liquid-distributing means for said secondary compartment; effluent collecting means receiving supernatant liquid of said secondary compartment and having an overflow level disposed at elevation sufficiently high for determining the normal surface level of the liquid within the tank; means for impelling sedimented material from diverse sections of the floor of the secondary compartment towards and into said passage area for passage into said primary compartment; means for passing sedimented material from the primary compartment; means comprising a pump for passing liquid from said supernatant liquid-collecting means of the primary compartment to said secondary liquid-distributing means in quantity greater than that of the quantity of liquid overflowing into said secondary effluent collecting means for thereby realizing a certain back-flow of liquid from the secondary compartment through said passage area into said primary compartment.

8. A unit as defined in and by claim 7, in which there is included as part of the means that includes said pump a branch for passing a quantity of the thereby pumped liquid to the primary feed-receiving and distributing means.

9. A liquid-holding settling tank having a partial partition dividing the tank into functionally separate primary and secondary compartments that are in constant hydraulic communication through a passage area left because of the parti-

tion being only a partial one, liquid distributing means for and corresponding to each compartment, means by which initially supplied incoming liquid is passed to the liquid-distributing means for the primary compartment, supernatant collecting means at the upper portion of and serving only the primary compartment, supernatant collecting means at the upper portion of and serving only the secondary compartment, means leading from the collecting means of the secondary compartment for releasing from the tank as clarified supernatant liquid a quantity of liquid corresponding to the quantity of initially supplied incoming liquid that is passed to the liquid-distributing means of the primary compartment, common sludge removal means for said compartments, and mechanical means for establishing and maintaining a positively impelled flow of liquid from the collecting means for the primary compartment into the liquid-distributing means of the secondary compartment sufficient in quantity to establish back-flow from the secondary compartment through said passage area and into the primary compartment.

10. A liquid-treating tank for gravity separation of settleable solids from liquids, partitioning means therein providing only a partial partition

by which the interior liquid-holding portion of the tank is divided into a feed-receiving primary compartment and a subsequent secondary compartment, which compartments are in constant 5 hydraulic communication through passage area below a lower edge portion of the partitioning means that is spaced from an underlying bottom portion of the tank, liquid feed means and liquid withdrawal means for each compartment, 10 means for withdrawing liquid from the initial feed-receiving compartment and for delivering the thus withdrawn liquid into the secondary compartment for continuously maintaining a back flow of liquid from the secondary compartment 15 through said passage area into the feed-receiving primary compartment, a sump in the bottom of the tank and having extent under the liquid undergoing sedimentation in the primary compartment, means for impelling sedimented 20 material from diverse portions and the lower sections of the primary and secondary compartments towards and into said sump, and means for passing sedimented material from within said sump to a region outside of the tank.
